FIG. 6

UNITED STATES PATENT OFFICE.

JOSEPH C. FELDMAN, OF NEW YORK, N. Y., ASSIGNOR TO TILLIE K. FELDMAN, OF NEW YORK, N. Y.

ELECTRICAL WATER-HEATER.

1,299,159.

Specification of Letters Patent.

Patented Apr. 1, 1919.

Application filed September 23, 1918. Serial No. 255,287.

To all whom it may concern:

Be it known that I, JOSEPH C. FELDMAN, a citizen of the United States, and a resident of the city of New York, borough of Manhattan, in the county and State of New York, have invented a new and Improved Electrical Water-Heater, of which the following is a full, clear, and exact description.

This invention relates to automatic electric heaters, and among the objects of the present improvement is to provide a structure of relatively small dimensions whereby it is easily transported in one's grip or suit case for easy attachment to any convenient 15 electric plug or socket.

Another object of the invention is to provide a small compact automatic heater for water or other liquids having foldable legs so arranged as to provide a broad base in practice, but which will occupy a relatively 20 small amount of space when being packed or carried.

A further object of the invention is to provide an improved switch device whereby 25 the heating current will be completed automatically with the simple movement of the delivery valve to open position for hot fluid, but which is inoperative or inactive when the same valve is turned in the opposite direction to deliver cold fluid.

Another object of the invention is to provide an automatic switch so constructed and arranged that when the faucet is turned toward closed or neutral position far enough 35 to break the circuit the circuit cannot again be closed to heat the coils unless the faucet is first turned to substantially complete neutral or mid position.

Another object of the invention is to prevent 40 the stopping of the flow of water with the switch closed.

With the foregoing and other objects in view the invention consists in the arrangement and combination of parts hereinafter 45 described and claimed, and while the invention is not restricted to the exact details of construction disclosed or suggested herein, still for the purpose of illustrating a practical embodiment thereof reference is had to 50 the accompanying drawings, in which like reference characters designate the same parts in the several views, and in which

Figure 1 is a vertical sectional view of my present improvement, the faucet being shown 55 adjusted to deliver hot water.

Fig. 1^a is a view in front elevation in diagram indicating the use of the improvement as a support for a jar of water with a hose leading therefrom to the base of the heater.

Fig. 2 is a horizontal section on the line 2-2 of Fig. 1.

Fig. 3 is a plan view of the porcelain core showing the relation of the heating coil and binding posts therefor.

Fig. 4 is a view showing the switch mechanism in normal position, the switch casing being shown in section on substantially the line 4-4 of Fig. 1.

Fig. 5 is a view similar to Fig. 4, but showing the switch closed.

Fig. 6 is another view of the same mechanism indicating the action of the safety guard; and

Fig. 7 is a detail perspective view of the guard.

Referring now more specifically to the drawings, I show an automatic water heater, and by the term "water" as employed hereinafter I wish to be understood as covering broadly any liquid or fluid to be delivered through or from the faucet, comprising a base 10 of any suitable material having an inlet port 11 with which is associated a coupling nipple 12 for connection with any source of supply of water, such for example 85 a standard water faucet, reservoir, or as indicated in Fig. 1^a a jar 13 from which a tube 14 conveys the water to the nipple. The base is bored transversely forming a seat 15 for the plug 16 constituting the rotatable 90 member of the faucet. A handle 17 connected to the plug serves to manipulate the same and indicate its position. 18 indicates a delivery nozzle held from movement upon the outer end of the plug as by means of a 95 bracket 19 fixed to the front of the base. The upper portion of the base is bored at 20 and 21, these bores being vertical and having lower ends merging into the seat 15. The upper end of each bore 20 or 21 is also 100 counterbored as at 22.

The base is provided with pairs of downwardly projecting lugs 23 between each pair of which is pivoted at 24 a leg 25 of any suitable design. These legs are preferably 105 three in number so as to insure steadiness of support, and two of them are arranged at the front on opposite sides of the faucet and having a wide bearing insure maximum stability for the heater in the manipulation of 110

the faucet plug, it being borne in mind that the entire device is relatively small and otherwise would be comparatively easy to tilt or upset. The means for connecting the 5 legs to the base, however, provides for easy nesting of the legs since they are adapted to swing toward one another or the vertical axis of the heater, and they occupy no more width of space than the main portion of the 10 heater.

The faucet plug 16 is bored centrally from each end as shown at 26 and 27 leaving, however, a wall 28 separating these two bores. In one position of the plug as shown in Fig. 15 1 the bores 11 and 20 are brought into communication through lateral ports 29 and 30 both of which communicate with the axial bore 26. At this time the delivery bore 27 is in communication with the bore 21 through 20 a port 31. 32 indicates a by-pass communicating with the inner end of the bore 27 and extending rearward over the wall 28 as far as the vertical axis of the bore 11 with which it communicates when the plug is turned 25 through 180 degrees from the position of Fig. 1. Thus the inlet bore 11 is brought into direct communication through the by-pass 32 with the delivery bore 27. Those portions of the plug at this time adjacent to the bores 20 30 and 21 serve to seal the same. The front portion of the base carries two stop lugs H and C with which the handle 17 is adapted to operate. When the handle is turned to strike the lug H hot water will be delivered, and 35 when the handle is swung upward and around against the lug C cold water will be delivered. Obviously these lugs serve to limit the extent of rotation of the plug in either direction from the normal position in 40 which the handle 17 is upright. The plug is held in the tapered seat 15 by a nut 33 on the outside of which is a lock nut 34 having a flange 35 extending inward over the nut 33. The periphery of the lock nut 34 is provided 45 with a series of teeth 36 as shown in Figs. 4, 5, and 6.

Above the base is a core 37 made of porcelain or its equivalent and provided with a multiplicity of vertical holes extending entirely through the same. Two of these holes 50 38 and 39 communicate respectively with the base bores 20 and 21. The lower end of the core is provided with a pair of bosses 40 surrounding the lower ends of the holes 38 and 55 39 and which project into the counterbores 22 of the base and so positively hold the core from rotation, when the shell 41 surrounding the core is being screwed into the internally threaded rim 42 at the top of the base. Any 60 suitable packing or gasket means is fitted between the core and the top of the base to prevent leakage. Except for the bosses 40 both upper and lower ends of the core are flat and smooth. Between the holes 38 and 39 are a 65 multiplicity of holes 43 through all of which

the water passes after it leaves the hole 38. The flow of water from the hole 38 to the first hole 43 is through a depression or bypass 44 formed in the upper end of the core below the flat surface thereof. Another bypass 45 leads from the bottom of the first hole 43 to the lower end of the second hole 43, and thence communication is made through all of the remaining holes 43 70 through alternately located upper and lower 75 by-passes 44 and 45.

In addition to the holes 38, 39, and 43 the core is provided with sockets 46 into which are fitted a pair of binding posts 47 and 48.

The water passing through the core from 80 the hole 38 to the hole 39 is almost instantaneously heated by a resistance device within the core and comprising a series of coils 49, one located in each of the holes 43. One end of the resistance device is fixed at 50 in 85 the binding post 47 and extends thence to the nearest coil 49 along a by-pass similar to the by-passes 44. Thence the direction of the coil or wire connecting each coil with the next follows the same course as the flow of 90 water through the consecutive holes and by-passes 45, the resistance wire finally, however, leading from the last coil 49 to the binding post 48 at the point 51.

The binding posts project upward from 95 the core into any suitable cap or dome 52 secured in or to the shell 41. A pair of conductors 53 and 54 are connected respectively to the upper ends of the binding posts 47 and 48 within the dome and lead outward therefrom through outlets 55 fitted in slots 56 formed in the rear wall of the dome. The lower edge of the dome as indicated in Fig. 1 may serve to hold the locking ring 57 in 100 place, which serves to seal the upper end of 105 the core by means of a gasket 58 fitted against the smooth top thereof. The top of the dome is provided with a neck 59 which may serve as a holder or support for any device such as the jar 13.

Under normal conditions when no water is to be delivered or when cold water is to be delivered it is obviously undesirable to permit a current to pass through the resistance member, and hence I provide means to automatically control the current simultaneously with the control of the hot water delivery. 115 60 indicates a switch casing shown as located at the rear of the heater and within which the lock nut or mutilated gear is located at 120 the rear of the faucet plug. The main conductor is located at 61 leading into one side of the casing 60. This feature may be regarded as an ordinary double wire electric cord of any suitable length and adapted to be 125 attached in any well known or conventional manner with any convenient electric socket. One wire 62 is connected within the casing to a tumbler 63 and directly or electrically to a 130 knife blade 64 carried by the tumbler. The

knife blade is adapted to engage with the two blades 65 constituting thereby a well known type of knife blade switch. The two blades 65 are supported upon a block of insulation 66 in the top of the casing, and from these blades the wire 53 leads through an outlet 67 into the dome as previously set forth. The other wire 54 leading from the binding post 48 extends from the dome and into the top of the switch casing through an outlet 68, and becomes a part of the double wire cord 61.

The tumbler is pivoted at 69 and is normally urged downward by means of a spring 70 anchored at 71 so as to hold or tend to hold the knife blade 64 separated from the blades 65, breaking the circuit through the heater. This normal position is shown in Fig. 4 at which time the faucet handle is upright and the water inlet port 11 is closed by the imperforate portion of the plug between the port 29 and the by-pass 32. The tumbler 63 carries a tubular member 72 in which is a reciprocating bolt 73 having its outer end beveled and which carries a pin 74 projecting laterally through a slot 75 formed in the tube 72. The pin 74 prevents rotation of the bolt in the tube, and it also limits the endwise movement of the bolt. A spring 76 within the tube tends to force the bolt outward or away from the pivot 69.

77 is a fixed vertical guide adjacent to the mutilated gear 34 and in this guide is a vertically reciprocating rack 78 with the teeth of which the teeth 36 aforesaid are adapted to mesh when the faucet is turned to deliver hot water, the direction of rotation of the faucet for this purpose being indicated by the arrow *h*. When, however, the faucet is turned in the direction of the arrow *h* the teeth 36 move downward and away from the rack. In the normal idle position as shown in Fig. 4 the point of the bolt 73 lies just above the rack 78, and so with the actuation of the rack upward by the turning of the faucet in the direction of the arrow *h* the bolt will be lifted, swinging it and the entire tumbler around the pivot 69, and against the force of the spring 70. The rack or plunger 78 when thus forced upward in the stationary guide 77 causes the beveled end of the bolt 73 to wipe against the face of an abutment 79 fixed on about the same level as the tumbler pivot, and during the continued upward movement of the plunger 78 the bolt 73 is thus caused to telescope inward against the force of the spring 76 causing the pin 74 to move toward the right along the slot 75. 80 is a guard member pivoted at 81 on a fixed arc shaped bracket 82. This guard may be described as being dart shaped having two edges 83 and 84 meeting at the upper end in an acute angle or point 85. The edge 83 is normally vertical while the heel portion 86 of the guard rests upon a fixed lug 87 carried by the bracket 82, this position being maintained by a spring 88 anchored at 89 and bearing against the edge 84 of the guard. The inner face of the guard constitutes a cam 90 located normally just above the pin 74, hence when the bolt 73 is lifted as just described the pin strikes against the lower edge of the cam 90 and wipes along the curved surface thereof while the bolt is being lifted and moved inward against the force of the spring 76. The parallel dotted lines 91, Fig. 4, indicate an approximation of the path of the pin in its upward movement. Consequently the guard is tilted to the right around its pivot 81 during its upward movement. When, however, the pin passes the point 85 of the guard the spring 88 will snap the guard back to normal position, and as shown in Fig. 5 the pin 74 will be above and at the right of said point 85 and the cam 90.

When the faucet is turned back to or toward normal position the rack or plunger 78 will be drawn downward positively by the gear teeth 36. The spring 70 then acts promptly to draw the tumbler downward withdrawing the blade 64 from the blades 65. The pin 74, however, coming down with the tumbler will wipe against the edge 84 of the guard and cam whereby the bolt 73 will be held retracted or telescoped within the tube 72 with the result that the point of the bolt will be withdrawn from over the end of the plunger, and when the tumbler is swung far enough downward to permit the pin 74 to pass beneath the cam 90 the beveled end of the bolt will be snappel by virtue of the spring 76 against the face of the plunger as in Fig. 6. The circuit now is broken and if through carelessness or inadvertence the operator should turn the handle again to the left for the delivery of hot water without first returning the plunger 78 to its down position as in Fig. 4, the water will not be heated. This arrangement of switch controlling devices insures, therefore, that when the flow of hot water is to be stopped the operator must turn the handle until it becomes upright, and when this takes place the plunger 78 will be lowered far enough for the bolt 73 to be projected over it as in Fig. 4. As will be seen in Fig. 6 the plunger may be operated freely up and down without affecting the position of the tumbler or knife blade, unless and until the plunger is moved far enough downward to pass the point of the bolt. The pin 74 in its downward movement with the tumbler has little or no frictional engagement with the guard in the beginning of its movement and so the full force of the spring 74 at its maximum tension acts to insure the prompt withdrawal of the knife blade 64 from the blades 65, but after the switch is opened in this manner

the pin 74 bearing against the lower portion of the cam along the edge 84 will compress the spring 76 and so cushion somewhat the effect of the spring 70.

5 It will now be seen that the faucet may be turned freely any where between normal and the position for delivering cold water without operating the switch, but when turned to deliver hot water the switch will 10 be automatically closed, and subsequently the switch will be opened breaking the circuit when the hot water is shut off. The switch mechanism is relatively simple in construction and is safe and reliable in practice.

15 I claim:

1. In switch devices for automatic water heaters, the combination of relatively fixed and movable switch members, a tumbler to 20 which the movable member is attached, said tumbler including a telescopic bolt, a member acting against the bolt to move the tumbler, and means to cause movement of the bolt in and out of the tumbler during the 25 movements of the tumbler.

2. In automatic switch devices for water heaters, the combination of relatively fixed and movable switch members, a pivoted tumbler to which the movable member is 30 attached, said tumbler having a tubular socket the axis of which is radial with respect to the pivot thereof, a bolt slidably fitted in said socket, hand controlled means acting against the bolt to cause it and the 35 tumbler to move around the pivot to bring the movable member into or out of engagement with the other members, and means acting upon the bolt serving to move it along the socket while the tumbler swings 40 around its pivot.

3. In switch devices for automatic water heaters, the combination of relatively fixed and movable switch members, a tumbler to

which the movable member is attached and including a tubular socket, a bolt fitted 45 slidably in said socket, a spring within the socket tending to project the bolt therefrom, a member acting against the projecting end of the bolt serving to move it and the tumbler to close the switch, means acting on the 50 tumbler to restore it to normal position breaking the switch, and means acting upon the bolt to force it inward against the socket spring when the tumbler is drawn back toward normal position.

4. In switch mechanism for automatic water heaters, the combination of relatively fixed and movable switch members, a tumbler to which the movable member is secured and having a tubular socket, a spring 60 in said socket, a bolt fitted slidably in the socket against the spring and projected thereby from the socket, a plunger acting against the bolt to move it and the plunger to close the switch, means acting to return the tumbler automatically to normal position 65 breaking the switch, and a movable guard member acting upon the bolt to withdraw it from the plunger when the tumbler is being restored to normal position.

5. The herein described switch mechanism comprising relatively fixed and movable contact members, a movable tumbler to which one of the contact members is connected, said tumbler having a tubular socket, 70 a bolt slidably fitted in said socket, a hand controlled plunger acting against the bolt to move the same and the tumbler in one direction, automatic means acting upon the tumbler to move it in the opposite direction, 75 said bolt having a laterally projecting pin, and a movable guard cooperating with the pin to cause the bolt to move out of contact with the plunger when said automatic tumbler operating means is operated.

JOSEPH C. FELDMAN.
